UNITED STATES PATENT OFFICE

FRITZ WINKLER AND HANS HAEUBER, OF LUDWIGSHAFEN-ON-THE-RHINE, GERMANY,
ASSIGNORS TO I. G. FARBNINDUSTRIE AKTIENGESELLSCHAFT, OF FRANKFORT-
ON-THE-MAIN, GERMANY, A CORPORATION OF GERMANY

PRODUCTION OF LIQUID HYDROCARBONS FROM OLEFINES

No Drawing. Application filed May 4, 1928, Serial No. 275,255, and in Germany May 27, 1927.

This invention relates to an improved process for the manufacture and production of liquid hydrocarbons, including those of the aromatic series, from olefines.

5 It has already been suggested to produce liquid hydrocarbons by acting on gases comprising olefines at an elevated temperature and at any convenient pressure, with precious metals or copper, preferably in a form exhibiting coherent surfaces.

We have now found that use may also be made, in the said process, of alloys of gold, silver or copper, such as brass, bronze, manganese-copper, and the like, as also of tinned or 15 zinc-coated, aluminized or chromium coated iron, copper or other metals resistant to heat, with excellent results. The above coating metals all form amphoteric hydroxides which are not precipitated from alkaline solutions 20 by hydrogen sulphide. Under "metals resistant to heat" are to be understood those which by the action of heat lose neither their shape nor their resistance to mechanical attack. In this case also, it is sufficient under certain 25 conditions, if the reaction chamber, for example, a reaction tube, alone be constructed of the specified materials. The employment, for example, of internally tinned copper tubes may be preferable over ordinary copper 30 tubes, because, under certain conditions, these latter become brittle after prolonged use at high temperatures, which drawback is not observed when using tinned tubes.

The operation according to the present invention is usually carried out at temperatures ranging from 300° to 800° C. but preferably at about 750° C. and the pressure may be atmospheric, but pressures of 5, 20, 200 or even 1000 atmospheres may be employed.

40 The following examples will further illustrate the nature of this invention, but the invention is not restricted thereto.

Example 1

45 2.2 liters of ethylene are passed per hour through an inside zinc-coated iron tube, 60 centimeters long and 15 millimeters internal diameter, heated to 800° C. With a single passage of the said gas, 100 grams of the 50 original gas furnish about 37 grams of a

condensate, 70 per cent of which boil below 200° C. The condensate contains about 5 per cent of tar, and the exhaust gases contain about 45 per cent of methane. The tar contains naphthalene and anthracene. Even after a long working period, no deposition of carbon takes place in the tube.

Example 2

55 Ethylene is passed, at the rate of 15 liters per hour, through a tinned copper tube heated to 750° C. A yield of about 8 grams of a yellow condensate, free from tar, is obtained per 100 grams of the initial gas when passing it only once through the tube. The exhaust 65 gas contains only 3 per cent of methane, 0.6 per cent of hydrogen, the remainder consisting of ethylene. Here again, no deposition of carbon in the heated tube is observed.

60 If gases, containing 20 to 40 per cent of ethylene, propylene, butylene, or the like, such as are obtained for example in treating coal, tars and mineral oils at temperatures of about 800° C. with superheated steam in the absence of metals, which further the 75 production of carbon dioxid from carbon monoxid and steam, be employed for the production of liquid hydrocarbons, the operation may be conducted at 800° C. with reduced velocity of the gas current in the heated 80 tube, without any carbon being deposited or any appreciable amount of tar being formed.

What we claim is:—

1. In the production of liquid hydrocarbons at an elevated temperature from gases comprising olefines, the step of acting on the said olefines with a catalyst consisting of a metal resistant to heat superficially coated with a metal selected from the group consisting of tin, zinc, aluminium, and chromium 65 at temperatures of between about 300° and 800° centigrade.

2. A process for the production of liquid hydrocarbons, which comprises passing ethylene through a zinc-coated iron tube heated to 95 about 800° C.

3. In the production of liquid hydrocarbons at an elevated temperature from gases comprising olefines, the step of acting on the said olefines at temperatures of between 300° 100

and 800° centigrade with a catalyst consisting of a metal in a form exhibiting coherent surfaces superficially coated by heat treatment with a metal selected from the group consisting of tin, zinc, aluminium and chromium.

- 5 4. In the production of liquid hydrocarbons at an elevated temperature from gases comprising olefines, the step of acting on the said olefines at temperatures of between 300°
10 and 800° centigrade in an apparatus, the inner surfaces of which consist of a metal in a form exhibiting coherent surfaces superficially coated by heat treatment with a metal selected from the group consisting of tin, zinc,
15 aluminium and chromium, the said materials of the apparatus also acting as a catalyst.
20 5. A process for the production of liquid hydrocarbons, which comprises passing a gas comprising an olefine at a temperature of between 300° and 800° centigrade through a tube consisting of a metal in a form exhibiting coherent surfaces the inner surface of which is superficially coated by heat treatment with a metal selected from the group
25 consisting of tin, zinc, aluminium and chromium.

In testimony whereof we have hereunto set
our hands.

FRITZ WINKLER.
HANS HAEUBER.
